UNITED STATES PATENT OFFICE.

WILLIAM McCRRORY, OF DETROIT, MICHIGAN.

IRONING BOARD.

Application filed September 12, 1921. Serial No. 500,050.

To all whom it may concern:

Be it known that I, WILLIAM McCRRORY, a citizen of the United States, residing at Detroit, in the county of Wayne and State 5 of Michigan, have invented a new and useful Ironing Board, of which the following is a specification.

This invention relates to ironing boards and relates particularly to ironing boards 10 having relatively small boards attached.

It is the object of the invention to provide an ironing board having an opening wherein an auxiliary board of relatively small dimensions is normally stored flush 15 with the top of the main board, said auxiliary board being adjustable for use to an elevation above the main board, and locking means being provided for maintaining such raised position.

20 In attaining this object the invention contemplates providing a seat for the auxiliary board within the opening of the main board, and toggle arms for supporting the auxiliary board in raised position, which arms 25 are normally concealed beneath the main board, and a handle-controlled latch mechanism engageable with the toggle arms in raised position to positively maintain said position.

30 A preferred embodiment of the invention is hereinafter described and illustrated in the accompanying drawings, wherein,

Fig. 1 is a view in side elevation of the improved board with the auxiliary board in 35 stored position.

Fig. 2 is a longitudinal vertical section of the same, showing the auxiliary board elevated for use.

Fig. 3 is a bottom view of the invention 40 with the auxiliary board stored.

Fig. 4 is a cross-section taken on line 4-4 of Fig. 3.

In these views the reference character 1 45 designates an ironing board having substantially the usual shape and dimensions, and having the central opening 2. Said opening is adapted to receive a relatively small auxiliary board 3, of lesser thickness than the main board, the latter being formed 50 marginally of the opening 2 with a seat 4 for said auxiliary board. When engaged with the seat, the auxiliary board is substantially flush with the top of the main board, as is best illustrated in Fig. 4. To permit 55 the auxiliary board to be raised, when desired, to the position of use shown in Fig.

2, there is employed a toggle mechanism comprising a pair of legs 5 pivotally attached to each end of the board 3, therebeneath, as by the brackets 6, and corresponding links 7, which are terminally pivotally connected respectively to the lower ends of the legs 5 and to a pair of brackets 8, centrally depending from the main board, at each side of the opening 2. Brace rods 65 9 rigidly connect the links 7 extending from each pair of legs 5. When the auxiliary board is in its stored position the legs 5 and links 7 are positioned beneath the main board, forming with each other an angle of 70 approximately forty-five degrees, as shown in Fig. 1. When, however, the auxiliary board is elevated for use, as is seen in Fig. 2, the legs 5 project for the greater portion 75 of their lengths above the board 1, and the links 7 extend slightly upward from the brackets 8 to said legs. Thus the angles between said legs and links is somewhat in excess of ninety degrees when the auxiliary board is raised. Notches 10 and 10' are 80 respectively formed in the pivotally connected ends of the legs 5 and links 7, which notches are in registration when the auxiliary board is in raised position. To maintain said 85 raised position there is transversely mounted beneath each end of the board a shaft 11, carrying rollers 12 respectively engageable with the registering notches 10 and 10'. Said shafts are each terminally journaled in plungers 13 slidable lengthwise of the 90 board 1 in brackets 14 secured to the bottom of said board at each side of the opening 2 therein.

The two shafts 11 are urged toward each other by springs 15 coiled upon the plungers 95 13, the response of said shafts to said springs being limited in the normal or lowered position of the small board by engagement of the rollers 12 with the upper portions of the legs 5 and in the raised position of said board by engagement of said 100 rollers in the notches 10 and 10' of the legs 5 and links 7. Shifting of the auxiliary board either from its raised to its lowered position, or vice versa, involves a retractive 105 movement of the shafts 11 which movement is yieldably resisted by the springs 15. When pressure is upwardly applied to the small board 3, for the purpose of raising the same, the resistance of the springs 15 is 110 overcome gradually, as the legs 5 ride up upon the rollers 12, so that elevation of the

board may be accomplished with slight manual effort. Lowering of the auxiliary board, however, requires the exertion of a considerably greater downward pressure, 5 since the retraction of the shafts 11 must be abruptly accomplished.

For locking the toggle mechanism comprised by the legs 5 and links 7, so as to positively hold the auxiliary board in its raised 10 position, there is provided a mechanism comprising a crank-shaft 16 journaled transversely below the board 1 in the brackets 8, and a pair of pull rods 17, oppositely extending from the reverse crank throws 18 of 15 said shaft and respectively terminally engaging the shafts 11. Preferably the rods 17 are passed transversely through the shafts 11, and are engaged beyond the latter by nuts 19 adjustable to vary the relation of 20 said pull rods and shafts. The crank-shaft 16 is bent at one end to form a handle as indicated at 20, said handle projecting normally downward as indicated in Fig. 1. When, after establishing the auxiliary board 25 in elevated position, it is desired to lock said board in said position, it is necessary only to rock the shaft 16 to the position shown in Fig. 2, in which position the crank throws 18 are substantially horizontal, establishing an overlapping relation between the 30 adjacent ends of the pull rods 17 and stressing the shafts 11 toward each other so as to firmly press the rollers 12 into the notches 9 and 10 of the legs 5 and links 7. When 35 the auxiliary board 3 is thus held in raised position, the upper ends of the legs 5 bear against the brackets 6 in such a manner as to insure against swinging of said legs. Unlocking is effected by merely swinging the 40 handle 20 back to its normal vertical position.

It is to be understood that raising or lowering of the auxiliary board is effected by

manually subjecting said board to a moderate upward or downward pressure. While 45 the effort of the springs 15 will maintain said auxiliary board raised, under the stresses ordinarily placed upon said board in use, it is preferred to employ the described locking mechanism so as to positively safeguard the auxiliary board against 50 accidental dropping.

The described invention makes the full sized board or the auxiliary board for small work available alternatively without waste 55 of time, and in a desirable compact form.

What I claim is:

1. In a device of the character described, the combination with an ironing board formed with an opening, of a relatively 60 small ironing board fitting normally within said opening, and removable from said opening to an elevated position of individual use above the main board, means for supporting the small board upon the main board 65 in the elevated position of the former, and spring means yieldably resisting movement of the small board from either of its two positions to the other one.

2. In a device of the character described, 70 the combination with an ironing board formed with an opening, of a relatively small ironing board fitting normally within said opening, and removable from said opening to an elevated position of individual 75 use above the main board, and a toggle mechanism for supporting the smaller board in its elevated position, comprising a pair of legs pivotally connected to the smaller board one at each end thereof, and links 80 having their ends pivoted respectively to said legs and to the middle portion of the main board.

In testimony whereof I sign this specification.

WILLIAM McCRRORY.
